United States Patent Office

Des. 192,438
Patented Mar. 20, 1962

192,438

BEVERAGE DISPENSER

Albert Henry Torongo, Newtown, Pa., assignor to The Procter & Gamble Company, Cincinnati, Ohio, a corporation of Ohio

Filed Mar. 14, 1961, Ser. No. 64,286

Term of patent 14 years

(Cl. D44—21)

FIG. 1.

FIG. 2.

FIG. 3.

FIG. 4.

FIG. 5.

FIG. 1 is a side elevational view of a beverage dispenser showing my new design, with the cover in place and the cap in open or dispensing position;

FIG. 2 is a rear elevational view thereof, with the cover removed;

FIG. 3 is a front elevational view thereof, with the cover removed;

FIG. 4 is a top plan view thereof, with the cover in place and the cap in closed position; and

FIG. 5 is a bottom plan view thereof.

I claim:

The ornamental design for a beverage dispenser, as shown.
